ENGINE CONTROL MECHANISM

Matt U. Jopperi and Charles I. Monaghan,
Ashtabula, Ohio

Application December 16, 1948; Serial No. 65,572

6 Claims. (Cl. 121—143)

1

The present invention relating generally as indicated to an engine control mechanism is more especially concerned with improvements in a control mechanism for deck winch engines such as are employed on boats for drawing in or letting out the mooring cables or ropes.

Hitherto deck winch engine operation has involved the manipulation of a lever on a reversing valve which controls forward and reverse operation of the winch engine and of a globe or like valve which controls the steam for operating the engine, such lever and valve being located adjacent the engine at the center of the boat and manipulated by an operator pursuant to signals given by an assistant stationed at the dock or pier side of the boat. Such control of the engine involves a great deal of hazard because the operator cannot directly observe what is going on and because of the possibility of the operator misinterpreting the signals given by the assistant or the assistant giving incorrect signals. In any case, the resulting improper operation of the winch engine may snap the cables or ropes which are wound and unwound from the winch drum driven by the engine and thus cause injury to workmen on the boat and on the dock or pier.

Accordingly, it is a primary object of this invention to provide a control mechanism for a deck winch engine which involves manipulation of but a single lever by an operator stationed at the dock side of the boat where he can observe the entire mooring operation.

Another object is to provide a control mechanism which through a single operating lever effectuates desired sequential operation of the engine reversing valve mechanism and the engine itself.

Another object is to provide duplicate controls on opposite sides of the boat whereby either may be operated depending upon which side of the boat the dock or pier is located.

Another object is to provide a control which is so arranged that admission of steam to the engine for operating the same is conditioned upon proper operation of the reversing valve mechanism thereof.

Other objects and advantages will become apparent as the following description proceeds.

To the accomplishment of the foregoing and related ends, said invention, then, comprises the features hereinafter fully described and particularly pointed out in the claims, the following description and the annexed drawing setting forth in detail one illustrative embodiment of the invention, this being indicative, however, of but one

2

of the various ways in which the principle of the invention may be employed.

In said annexed drawing—

Fig. 1 is a top plan view diagrammatically illustrating a boat and the adjacent dock;

Fig. 2 is a transverse cross-section view of the boat illustrating a duplicate control mechanism and the piping therefor;

Fig. 3 is a fragmentary cross-section view illustrating, on a somewhat enlarged scale, the upper left portion of Fig. 2;

Fig. 4 is a top plan view of one of the controls;

Fig. 5 is a cross-section view taken substantially along the plane indicated by the line 5—5, Fig. 4;

Fig. 6 is a cross-section view taken substantially along the plane indicated by the line 6—6, Fig. 7; and

Fig. 7 is a cross-section view taken substantially along the plane indicated by the line 7—7, Fig. 6.

Referring now more particularly to the drawing and first to Figs. 1—3 therein, there is shown a typical boat 1 including, for example, a pilot house 2 at its front end and an after-cabin 3 at its rear end, several deck winch steam operated engines 4 disposed centrally on the boat deck 5 and a corresponding number of pairs of engine control mechanisms 6 on opposite sides of the boat, said controls being operative, as will hereinafter appear, to selectively control the forward and reverse operation of the respective engines 4 and the admission of steam thereinto whereby to control the drawing in and letting out of the ropes or cables 7, which are wound on winch drums (not shown) driven by said engines 4, said ropes or cables 7 extending through chocks 8 at the sides of the boat and fastened to the conventional securing means fixed on the dock or pier 9.

Inasmuch as all of the engines and duplicate controls therefor are substantially the same, it will be necessary herein to only describe the operation and construction of but one of them.

Preferably located below the deck 5 and the associated engine 4 and winch drum driven thereby is a double-acting fluid motor 10 comprising, for example, a cylinder 11 provided with ports at its opposite ends and a piston 12 reciprocable in said cylinder having a piston rod 13 extending upwardly through the deck and connected to the usual slide reversing valve or the like (not shown) on the steam chest of the engine 4.

Also preferably located below the deck 5 but on opposite sides of the boat are a pair of control valves 14 each of which comprises a rotary disc valve below the deck operated by a rotatable lever 15 above the deck.

Each said valve 14 as best shown in Figs. 4-7 comprises a cylindrical housing 16 closed at its lower end to provide a flat upwardly facing seat 17 against which the downwardly facing flat seat 18 of a rotary disc-like valve member 19 is seated. Leading to such seat 17 in said housing is a central exhaust port 20 to which a pipe 21 is connected, said pipe 21 extending downwardly into the water hold 22 of the boat. Also leading to such seat 17 are a plurality of circumferentially arranged ports, of which the ports 23 and 24 are preferably circumferentially spaced 90° from each other with the pipes 25 and 26 connected thereto respectively connected to the ports at the lower and upper ends of the associated fluid motor 10 and the port 27 is spaced 135° from the ports 23 and 24 with the pipe 28 connected thereto leading to the steam chest of the associated engine 4. A pressure port 29 laterally through said housing and above said valve member 19 has a pipe 30 connected thereto leading from a steam supply line 31. Said lines 31 extend longitudinally of the boat on opposite sides thereof as shown in Fig. 2.

The valve member 19 is formed with a central port 32 only part-way therethrough constantly registering with the central exhaust port 20 in said housing 16 and a radially extending duct 33 joining the port 32 with a port 34, said latter port being adapted to selectively register with the ports 23 and 24 upon rotation of said valve member 19 in opposite directions. Said valve member 19 is further provided with two diametrically opposed ports 35 and 36 completely therethrough each circumferentially spaced 90° from port 34.

As evident from Fig. 7, when said valve member 19 is in the position shown, no steam under pressure can flow to the associated engine 4 or to the associated fluid motor 10. However, upon rotation of said valve member 45° in a counterclockwise direction, the ports 34 and 36 in said valve member will respectively register with the ports 23 and 24 in housing 16 whereupon steam under pressure above said valve member will flow through the ports 36 and 24 and through pipe 26 to the upper end of the fluid motor 10 to move the piston 12 downward and the exhaust from the lower end of said fluid motor will flow through pipe 25, ports 23 and 34, duct 33, ports 32 and 20 and pipe 21 into the water hold 22. Thereupon, further rotation of said valve member 45° more in the same direction will cause the ports 35 and 27 to be in register whereby steam is caused to flow through said ports and pipe 28 to the associated winch engine 4 thus driving said engine in a desired direction as determined by the positioning of a reversing valve 4A (see Fig. 2) on said engine by the prior actuation of fluid motor 10 as aforesaid, said valve 4A being of any well-known construction and having the handle 4B of its movable valve member connected to piston rod 13 of said fluid motor 10. In this case the counterclockwise rotation of said valve member will, as shown in Fig. 4, effect rotation of engine 4 through valve 4A in a direction to rotate the winch drum to draw in the cable or rope 7.

On the other hand, if said valve member 19 is rotated 45° in a clockwise direction from the position shown in Fig. 7, steam will flow through ports 35 and 23 and pipe 25 to the lower end of fluid motor 10 urging the piston 12 therein upward, the exhaust from the upper end of said fluid motor flowing through pipe 26, ports 24

and 34, duct 33, ports 32 and 20, and exhaust pipe 21 into the water hold 22. Then, further rotation of said valve member clockwise 45° more will effect operation of the engine in a reverse direction by steam flowing through the ports 36 and 27 and pipe 28 leading to the engine 4 through reversing valve 4A. As evident, such clockwise rotation of valve member 19 positions the engine reversing valve 4A so that the engine drives the winch drum to let out the rope or cable 7.

Rotation of said valve member 19 in opposite directions as aforesaid is effected through a rotary valve stem 37 having a pin 38 transversely therethrough with the projecting ends of said pin fitting into a slot diametrically across a boss 39 at the upper end of said valve member 19. Said stem 37 extends upwardly through a cover plate 40 which closes the top of housing 16 and which includes a stuffing box 41. Interposed between said cover plate 40 and said valve member 19 is a compression spring 42 operative to effect yieldable seating of the valve member against seat 17 thus supplementing the pressure of the steam acting on the upper surface of said valve member. Said stem 37 extends upwardly through deck 5 and keyed to the upper end of said stem is a gear 43.

Above said deck 5 is a supporting bracket 44 in which the upper end of stem 37 is journalled. Rotatably supported in said bracket 44 is a shaft 45 to the upper end of which the operating lever 15 is connected and to the lower end of which is keyed a pinion gear 46 in mesh with the gear 43 on the upper end of said stem, said pinion gear 46 preferably having a pitch diameter of substantially one-half that of the gear 43.

The operating lever 15 is pivotally connected between its ends to said shaft as by a pin 47 and a spring 48 interposed between said bracket 44 and one end of said lever urges the other end of said lever downwardly to a position for engagement with the circumferentially spaced stop lugs 49 to 54 formed on said bracket. Because of the 2:1 ratio between said stem 37 and said shaft 45, stops 49, 50 and 51 and stops 52, 53 and 54 are arranged 90° apart to enable the aforesaid 45° and 90° rotations of said valve member 19 in opposite directions from the "Off" position shown in Fig. 4. The stops 49-50 and 52-53 are such that when any one is engaged by the adjacent side of lever 15, said lever may be pivoted about pin 47, to thus raise the lever over the adjacent stop. The stops 51 and 54, however, project upwardly a distance such that said lever 15 cannot be raised thereover. The upper end surfaces of stops 50 and 49 are preferably inclined whereby the lever 15 may be rotated clockwise from a position engaging stop 51 to a position between stops 49 and 52 without stopping to raise the lever over stops 50 and 49 and likewise the upper end surfaces of stops 53 and 52 are similarly inclined whereby the lever 15 may be rotated counterclockwise from a position engaging stop 54 to a position between stops 49 and 52 without stopping to raise the lever over stops 53 and 52.

From the foregoing it is now understandable that the deck winch engines 4 can be operated in a desired direction by first rotating the associated operating lever 15 on the dockside of the boat in a desired direction to engage one of the stops 50 or 53 provided on the bracket member 44. The pause in the turning of said operating lever while the same is raised over the stop 50 or 53 engaged

thereby permits proper actuation of the associated fluid motor 10 and consequent operation of the reversing valve 4A in the engine to a desired position and finally further rotation of said operating lever 15 in the same direction admits steam into the engine 4 to operate the latter through said valve 4A in a direction as determined by the prior actuation of said fluid motor 10 and engine reversing valve 4A. Then, in order to reverse the engine 4 it is necessary first to return the operating lever to its initial "off" position as shown in Figs. 4 and 7 and then turn the same in a direction to reverse the fluid motor 10, lift it over the stop engaged thereby and further turn it to admit steam under pressure into the engine 4 through valve 4A.

With an engine control mechanism as herein disclosed the operator need only operate the one operating lever 15 and at the same time he will be stationed in the dock side of the boat whereby he can readily observe whether the ropes or cables 7 are to be drawn in or let out and accordingly manipulate the lever 15 without relying on signals from an assistant and without operating both a lever and a globe valve handle as was heretofore required. It is to be noted that the engines 4 are paired up whereby, if desired, one operator can operate the two adjacent control mechanisms 6 and thereby control the two ropes or cables 7 at the front portion of the boat and another operator can control the other adjacent pair of control mechanisms 6 for controlling the ropes or cables 7 at the rear portion of the boat. With mechanisms such as disclosed, the boat 1 can be quickly and surely drawn up to a position closely adjacent the dock 9 without the dangers incident to operation of known mechanisms.

Other modes of applying the principle of the invention may be employed, change being made as regards the details described, provided the features stated in any of the following claims, or the equivalent of such, be employed.

We therefore particularly point out and distinctly claim as our invention:

1. A control mechanism for a fluid pressure operated winch engine including a valve controlling forward and reverse operation of said engine, comprising a double-acting fluid motor for actuating said valve, a selector valve operatively connected to said engine and fluid motor, said selector valve comprising a housing provided with a plurality of ports in communication with said fluid motor, engine, and a fluid pressure supply source, and a movable valve member in said housing provided with a plurality of ports so arranged that movement of said valve member to one position establishes communication between such supply source and said fluid motor to predeterminedly actuate said fluid motor and thus the valve actuated thereby and movement of said valve member to another position establishes communication between such supply source and said engine through said first-mentioned valve.

2. A control mechanism for a fluid pressure operated winch engine including a valve controlling forward and reverse operation of said engine, comprising a double-acting fluid motor for actuating said valve, a selector valve operatively connected to said engine and fluid motor, said selector valve comprising a housing provided with a plurality of ports in communication with said fluid motor, engine, and a fluid pressure supply source, and a movable valve member in said housing provided with a plurality of ports so arranged that movement of said valve member in one direc-

tion successively establishes communication between such supply source and fluid motor and between such supply source and engine through said first-mentioned valve.

3. A control mechanism for a fluid pressure operated winch engine including a valve controlling forward and reverse operation of said engine, comprising a double-acting fluid motor for actuating said valve, a selector valve operatively connected to said engine and fluid motor, said selector valve comprising a housing provided with a plurality of ports in communication with said fluid motor, engine, and a fluid pressure supply source, and a movable valve member in said housing provided with a plurality of ports so arranged that in one position such supply source is isolated from said fluid motor and engine and that movement of said valve member in one direction from such position successively establishes communication between such supply source and fluid motor and between such supply source and engine through said first-mentioned valve.

4. A control mechanism for a fluid pressure operated winch engine including a valve controlling forward and reverse operation of said engine, comprising a double-acting fluid motor for actuating said valve, a selector valve operatively connected to said engine and fluid motor, said selector valve comprising a housing provided with a plurality of ports in communication with said fluid motor, engine, and a fluid pressure supply source, and a movable valve member in said housing provided with a plurality of ports so arranged that in one position such supply source is isolated from said fluid motor and engine, that movement of said valve member in one direction from such position successively establishes communication between such supply source and fluid motor, between such supply source and engine for operating said engine in a forward direction, and that movement of said valve member in an opposite direction from such position successively establishes communication between such supply source and fluid motor and between such supply source and engine for operating said engine through said first-mentioned valve in a reverse direction.

5. A control mechanism for a fluid pressure operated winch engine including a valve controlling forward and reverse operation of said engine, comprising a double-acting fluid motor for actuating said valve, a selector valve operatively connected to said engine and fluid motor, said selector valve comprising a housing provided with a plurality of ports in communication with said fluid motor, engine, and a fluid pressure supply source, a movable valve member in said housing provided with a plurality of ports so arranged that movement of said valve member in one direction successively establishes communication between such supply source and fluid motor and between such supply source and engine, and stop members cooperating with said valve member for temporarily arresting movement of said valve member upon establishment of communication between such supply source and fluid motor and for arresting subsequent movement of said valve member upon establishment of communication between such supply source and engine through said first-mentioned valve.

6. A control mechanism for a fluid pressure operated winch engine including a valve controlling forward and reverse operation of said engine, comprising a double-acting fluid motor for actuating said valve, a selector valve operatively connected to said engine and fluid motor, said selec-

tor valve comprising a housing provided with a plurality of ports in communication with said fluid motor, engine, and a fluid pressure supply source, and a movable valve member in said housing provided with a plurality of ports so arranged that movement of said valve member in either of two opposite directions successively establishes communication between such supply source and fluid motor and between such supply source and engine through said first-mentioned valve.
